UNITED STATES PATENT OFFICE.

PHILIP B. BEKEART, OF SAN FRANCISCO, CALIFORNIA, ASSIGNOR TO GEORGE A. REACH, OF PHILADELPHIA, PENNSYLVANIA.

BASEBALL.

Application filed January 7, 1924. Serial No. 684,775.

To all whom it may concern:

Be it known that I, PHILIP B. BEKEART, a citizen of the United States, and a resident of the city and county of San Francisco, State of California, have made a new and useful invention, to wit, Improvements in Baseballs; and I do hereby declare the following to be a full, clear, concise, and exact description of the same.

This invention relates particularly to base balls.

An object of the invention is to provide a base ball having a center formed of rubber or other material, or combination of materials in sections which is so constructed that the ball will not become flattened or cracked after being batted.

A further object of the invention is to provide a spherical center for base balls composed of a plurality of complementary sections, formed of solid rubber, or of a combination of rubber and other material around which the ball is constructed to a desired diameter by winding thread tightly thereon and enclosing the assembly within an outer cover.

A still further object of the invention is to provide a sectional, spherical base ball center formed of rubber or cork or other suitable resilient materials around which the layers of yarn may be wound to form a ball which will retain perfect spherical shape, and which will not become flattened, cracked or eccentric after having been played with.

Other objects of the invention are to provide a base ball which will be superior in point of simplicity, inexpensiveness of construction, positiveness of operation, facility and convenience in use and general efficiency. Other objects and advantages will appear as this description progresses.

In this specification and the annexed drawings, the invention is illustrated in the form considered to be the best, but it is to be understood that the invention is not limited to such form, because it may be embodied in other forms, and it is also to be understood that in and by the claims following the description, it is desired to cover the invention in whatsoever form it may be embodied.

In the accompanying one sheet of drawings.

Fig. 1 is an enlarged sectional view

through a base ball constructed in accordance with my invention.

Fig. 2 is an elevation of the second center shown in Fig. 1.

Fig. 3 is an elevation of Fig. 2 showing the sections in a separated position.

Fig. 4 is a modified form of a section center ball.

Fig. 5 is a separated view of the ball shown in Fig. 4.

Fig. 6 is a further modified form of a sectional ball center.

Fig. 7 is a still further modified form of ball center.

Ball centers may be formed of solid rubber or with a skin coating of rubber moulded around a center of other material, or as an alternative method a rubber coating may be hardened around the said center by baking or vulcanizing the same. In the latter forms it is practically impossible to apply the rubber coating to a uniform depth around the center sphere, and as a result the rubber coating may be thicker in certain places than in others. If a ball having rubber applied unevenly around the center or if a rubber center that is not properly vulcanized, is struck or batted, the force of the blow may cause the said center to give way, consequently causing the ball to become flattened and cracked out of its true spherical shape.

My invention contemplates a base ball having an adjustable center so constructed and arranged that a moving force might temporarily knock it out of round but it would readily return to its normal spherical shape and would not become flattened, even under the most arduous form of playing, and which will also retain its spherical shape in all atmospheric conditions.

In detail the construction illustrated in the drawings comprises a spherical core formed of rubber, or other equivalent resilient material. The core is formed of a plurality of complementary sections 1 and 2 which are so arranged that when the two sections are placed together a perfect sphere is formed. In Figs. 1 through 3 inclusive the ball core is formed of a sectional center 3 of resilient material having a coating of elastic material 4 moulded therearound to a uniform depth. In Figs. 4 and 5 the construction is modified by forming the core entirely of rubber 5, and also the sections

are formed of a different cut, than that indicated in Figs. 2 and 3. In Figs. 4 and 5 a hole 7 is moulded in the center of the respective sections to allow for more ready

5 compensation of the parts.

In Fig. 6 the core is formed of a plurality of sections 8, 9 and 10 all of which when assembled form a true sphere. In Fig. 7 the core has a plurality of connected open- 10 ings 11 passing diametrically therethrough.

The core, illustrated in any of the Figs. 2

through 7 inclusive, has layers of yarn or

thread 12 wound therearound, and the ten-

sion of the winding is regulated to adjust

15 the desired degree of resiliency of the sec-

tional core and ball. The thread material

12 is placed around the ball to the desired

diameter after which the whole structure is

enclosed in a leather or other resilient cover

20 13 stitched thereon.

A base ball constructed in the manner de-

scribed is conventional in all respects ex-

cept that the center core is formed of a plu-

25 rality of sections which may adjust them-

selves, one relative to the other, to compen-

sate for undue pressures applied thereto.

Furthermore the construction of the ball

center in sections permits of expansion and

contraction, which is bound to occur by

30 reason of atmospheric conditions, so that the

ball will at all times retain its true spheri-

cal shape. My experience with a base ball

of this character has demonstrated that it eliminates the possibility of the base ball be- 35 coming flattened or the center becoming cracked or otherwise distorted. The center core being itself adjustable it will always assume its normal spherical condition after being struck a blow and will not continue to remain flattened or cracked as in the case 40 of a solid spherical core formed either of rubber or of cork or a combination of dif- ferent materials having rubber therearound.

Having thus described this invention, what I claim and desire to secure by Let- 45 ters Patent is:—

1. A base ball comprising a spherical cen- 50 ter formed of a plurality of comple- mentary sections of material having a coat- ing of rubber on the periphery thereof; lay- 55 ers of thread wound upon said sectional cen- ter core; and an outer cover enclosing said layers of thread.

2. A base ball comprising a spherical cen- 55 ter of material having resilient rubber there- on; said center being divided into a plural- ity of complementary sections; layers of thread wound upon said center and an outer cover enclosing said layers of thread.

In testimony whereof I have hereunto set 60 my hand at San Francisco, California, this 26th day of December 1923.

PHILIP B. BEKEART.
